UNITED STATES PATENT OFFICE.

JOHN C. BOYTON, OF CLEVELAND, OHIO.

DESIGN FOR AN ELECTRICAL-CONDUIT FITTING.

50,462.

Specification for Design.

Patented Mar. 20, 1917.

Application filed January 26, 1917. Serial No. 144,792. Term of patent 14 years.

To all whom it may concern:

Be it known that I, JOHN C. BOYTON, a citizen of the United States, residing at Cleveland, in the county of Cuyahoga and State of Ohio, have invented a new, original, and ornamental Design for Electrical-Conduit Fittings, of which the following is a specification, reference being had to the accompanying drawing, forming part hereof, wherein—

Figure 1 is a plan, Fig. 2 a side elevation, and Fig. 3 an end elevation of the electrical conduit fitting exhibiting my new design.

I claim:

The ornamental design for an electrical conduit fitting as shown.

JOHN C. BOYTON.
